publication with color drawing(s) will be provided by the Office upon request and payment of the necessary fee.

FIG. 1 is a front view of the first embodiment of the claimed design;

FIG. 2 is a rear view of the claimed design of FIG. 1;
FIG. 3 is a left side view of the claimed design of FIG. 1;
FIG. 4 is a right side view of the claimed design of FIG. 1;
FIG. 5 is a perspective view of the claimed design of FIG. 1;

FIG. 6 is an enlarged bottom view of the claimed design of FIG. 1;

FIG. 7 is an enlarged top view of the claimed design of FIG. 1;

FIG. 8 is a front view of the second embodiment of the claimed design;

FIG. 9 is a rear view of the claimed design of FIG. 8;

FIG. 10 is a left side view of the claimed design of FIG. 8;
FIG. 11 is a right side view of the claimed design of FIG. 8;
FIG. 12 is a perspective view of the claimed design of FIG. 8;

FIG. 13 is an enlarged bottom view of the claimed design of FIG. 8;

FIG. 14 is an enlarged top view of the claimed design of FIG. 8;

FIG. 15 is a front view of the third embodiment of the claimed design;

FIG. 16 is a rear view of the claimed design of FIG. 15;

FIG. 17 is a left side view of the claimed design of FIG. 15;
FIG. 18 is a right side view of the claimed design of FIG. 15;
FIG. 19 is a perspective view of the claimed design of FIG. 15;

FIG. 20 is an enlarged bottom view of the claimed design of FIG. 15; and,

FIG. 21 is an enlarged top view of the claimed design of FIG. 15.

The superimposed areas encased in broken lines, shown in FIGS. 1-7 and 15-21, illustrates portions of the cutting tool for tree pruning and form no part of the claimed design.
